UNITED STATES PATENT OFFICE

96,182

DESIGN FOR A DISPLAY SIGN

Hyman Hammer, Chicago, Ill., assignor to Price
Brothers, Chicago, Ill., a corporation

Application April 15, 1935, Serial No. 56,395

Term of patent 3½ years

To all whom it may concern:

Be it known that I, Hyman Hammer, a citizen of the United States, residing at Chicago, in the county of Cook and State of Illinois, have invented a new, original, and ornamental Design for Display Signs, of which the following is a specification, reference being had to the accompanying drawing, forming a part thereof.

The figure is a perspective view of a display sign, showing my new design.

I claim:

The ornamental design for a display sign as shown.

HYMAN HAMMER.
